United States Patent

Des. 235,821
Patented July 15, 1975

235,821

GOLF GLOVE

Samuel Flaum, 155 E. 34th St., New York, N.Y. 10016

Filed July 30, 1973, Ser. No. 383,887

Term of patent 14 years

Int. Cl. D2—06

U.S. CL. D2—361

FIG. 4

FIG. 3

FIG. 2

FIG. 1

FIG. 1 is a palm side elevational view of a golf glove showing my new design;

FIG. 2 is a side elevational view thereof as seen from the left of FIG. 1;

FIG. 3 is an elevational view of the back of the glove;

FIG. 4 is a side elevational view as seen from the right of FIG. 1.

I claim:

The ornamental design for a golf glove, substantially as shown.
